UNITED STATES PATENT OFFICE.

JOHN W. ESKHOLME, OF EAST ORANGE, NEW JERSEY, ASSIGNOR TO RED STAR APPLIANCES, INC., OF STAMFORD, CONNECTICUT, A CORPORATION OF DELAWARE.

STAMP-CANCELING MACHINE.

Original application filed March 9, 1925, Serial No. 14,045. Divided and this application filed May 29, 1926. Serial No. 112,487.

The present invention relates to machines for handling envelopes, cards, and other flat objects, and is capable of a variety of uses.

It is an object of the invention to provide 5 for printing with ink on a sealed envelope or on a flat card, as for instance to cancel the stamp on an envelope and to print adjacent to the canceled stamp the name of the post office, a date, the hour and the permit 10 number of the user.

It is a further object of the invention to count the number of envelopes, cards, or other flat objects passed through the machine, not for the benefit of the Government 15 in calculating the amount of postage paid thereon, but for the information of the user of the machine.

Although the machine is capable of a wide variety of uses, its greatest utility lies in 20 sealing stamped envelopes and then canceling the Government stamp and counting the number of stamps so canceled. Envelopes to be used in this way may be of the character now furnished by the United States 25 Government and having the postage stamp formed directly in the paper of the envelope, or equally well, may be a plain envelope to which an adhesive Government stamp has been affixed.

30 When the sealed envelopes come from the machine with the stamps canceled, and with the name of the post office and the date printed thereon, they can be delivered in bulk to the post office and there can be distributed directly into the outgoing pouches without the delays and labor incident to first placing them face up on the sorting table and then passing them through the stamp canceling devices now commonly used by the 35 Government employees. In other words, much of the labor now required at the post office is done before the mail reaches the post office with a consequent saving in time in placing the mail in transit to its destination.

40 This application is a division of my co-pending application, Serial No. 14,045, filed March 9, 1925.

45 In the machine of the present invention suitable means are provided for successively feeding envelopes into the machine from a feeding platform of novel construction, moistening the flaps of the envelopes and

then sealing the envelopes. After being sealed, each envelope is forwarded by suitable means until it trips a printing mechanism which by its rolling movement over the travelling envelope cancels the postage stamp thereof and prints adjacent to the canceling imprint other vital data, such as the name of the post office, the date, and hour 55 of cancellation. Counting mechanism operatively connected with the printing device records the number of printed imprints and consequently, the number of stamps canceled. This printing mechanism itself is so 60 mounted that it can be swung upward into inverted position to give access to the dies and type with which it is equipped, and the type and dies are so secured in place that 65 their replacement is a matter of but a moment's work, no special tools being required.

70 The present invention more particularly relates to the means for operating the printing mechanism and handling the envelopes as they pass therethrough.

75 Manually controlled levers are provided for throwing the counting mechanism out of action, for throwing the printing roll out of action, and for throwing the inking roll out of action, when occasion may require, so that 80 if desired, the machine may be operated simply as an envelope sealing machine.

85 Power for the machine is supplied by an electric motor compactly mounted, and those rotating elements of the machine which travel at high speed are equipped with wooden bearing sleeves which are silent in operation and to which no lubricating oil need be applied by the operator. There is, therefore, no chance that dripping oil will mar or 90 soil envelopes or other articles being passed through the machine.

95 Other details and objects of the complete machine will become clear from the following detailed description taken in conjunction with the accompanying drawings.

Fig. 1 is a side elevation of the complete machine;

100 Fig. 2 is a sectional plan view of the same on the line 2-2 of Fig. 1;

Fig. 3 is an end elevation of the machine as it appears when viewed from the left of Fig. 1, certain parts being omitted for greater clarity;

Fig. 4 is a detailed plan view of the printing, counting and inking mechanism, with the cover plate of the machine removed, or more strictly speaking, is an horizontal section on the line 21—21 of Fig. 1;

Fig. 5 is an end elevation of the same, or a vertical section on the line 22—22 of Fig. 4;

Fig. 6 shows the inking mechanism as it appears in vertical section on the line 23—23 of Fig. 10;

Fig. 7 shows the printing mechanism as it appears in vertical section on the line 24—24 of Fig. 10;

Fig. 8 shows details of the counting mechanism as it appears in vertical section on the line 25—25 of Fig. 10;

Fig. 9 shows the counting mechanism as it appears in vertical section on the line 26—26 of Fig. 5;

Fig. 11 shows the inking mechanism as it appears in vertical section on the line 27—27 of Fig. 5;

Fig. 11 shows the inking mechanism as it appears in vertical section on the line 28—28 of Fig. 5;

Fig. 12 shows the printing mechanism as it appears in vertical section on the line 29—29 of Fig. 9;

Fig. 13 is a sectional detail of the printing drum and dies on the line 30—30 of Fig. 10;

Fig. 14 shows a lock for the printing mechanism as it appears in vertical section on the line 31—31 of Fig. 10;

Fig. 15 shows a part of the printing mechanism and corresponds to Fig. 6 excepting that a hinged support and elements carried thereby has been swung upward and over against the top of the machine and into the position where changes can be made in the printing dies. Certain elements of Fig. 6 are omitted from Fig. 15 for greater clarity of illustration;

Fig. 16 is an end elevation of the mechanism as shown in Fig. 15, when viewed from the left;

Fig. 7 is a plan view of the elements shown in Fig. 15;

Fig. 18 is a sectional detail of the printing drum and dies;

Fig. 19 is a transverse or vertical section on the line 36—36 of Fig. 18;

Fig. 20 is a transverse vertical section of the printing drum and dies on the line 37—37 of Fig. 18 and is closely related to Fig. 13;

Fig. 21 is a plan view of the printing drum stripped of the die holder which it normally carries;

Fig. 22 is a section of the die holder alone;

Fig. 23 is an end elevation of the same;

Fig. 24 is a plan view of the same when positioned as in Fig. 22;

Fig. 25 is a plan view of the die and its removable type;

Fig. 26 is a side elevation of the same;

Fig. 27 is an end elevation of the same;

Fig. 28 is a plan view of the stamp canceling die;

Fig. 29 is a side elevation of the same;

Fig. 30 is an end elevation of the same;

Fig. 31 is a perspective view of a removable type bearing the user's number;

Fig. 32 shows the means by which the type are held in the die, as it appears in section on the line 49—49 of Fig. 20;

Fig. 33 is a section on the line 50—50 of Fig. 32;

Fig. 34 shows one of the removable type in elevation with its printing face at the top;

Fig. 35 is a detail of the type holding spring;

Fig. 36 (sheet 2) indicates the appearance of a stamped envelope after it has been passed through the machine for cancellation of the stamp and for printing of the name of the post office and the date of cancellation.

Frame work and receiving platform (Figs. 1, 2 and 3).

The frame work of the machine comprises a cast metal base 1 to which is secured, by a plurality of bolts 2, a sub-base 3 integral with which is a vertical supporting plate 4 carrying a hub 5 to serve as bearing support for certain of the rotating elements. Secured to the vertical plate 4 by bolts 6 is a central sheet metal plate 7 on the flanged upper edge of which is bolted a sheet metal platform 8 which extends the entire length of the machine. To its down-turned rear edge (Fig. 3) is bolted a long lower apron 9 which extends throughout the length of the machine. On the front down-turned edge of platform 8 is a short lower apron 10 (Fig. 1) to which is hinged a vertical guide plate 11 (Fig. 1). At the hinged connection is a coiled spring 12 for controlling the position of guide plate 11.

Above platform 8 and supported by a rear wall 13 bolted thereto is a cover plate 14 which covers the left hand two-thirds of the machine as viewed in Fig. 1, and which serves as the support for certain adjusting mechanisms. The front edge of cover plate 14 is carried by a front wall plate 15 (Fig. 1) secured along its lower edge by bolts 16 to a short front apron 17 bolted to the down-turned front edge of platform 8.

The receiving platform for the envelopes to be sealed and then canceled is at the right hand end of the machine as viewed in Fig. 1, and includes a pair of anti-friction rollers 18, the details of which are shown in Fig. 2.

Platform 8 is provided with a pair of parallel slots 19 (Fig. 2) through which rollers 18 may project to contact with a stack of envelopes horizontally placed thereon. These rollers are suitably mounted to turn

freely on pins, and are arranged to be lowered flush with the plate 8 when occasion requires.

The machine of the present invention includes means for feeding the envelopes to a moistening device where the gummed flaps thereof are moistened, and means for subsequently sealing the moistened gummed flaps. The sealing is accomplished by means of two parallel rolls, 122 and 123, shown in Fig. 1, which rolls are suitably operated and act to forward the envelopes to the printing mechanism which will be hereinafter described. As the feeding, moistening, transferring and sealing mechanisms do not comprise a part of the present invention, a detailed description of these parts will not be given.

The printing mechanism (Figs. 1, 2, and 3 to 34 inclusive).

The lower roller 137 (Fig. 5) of the printing mechanism has a rubber face 138 and in all of its structural details is essentially like lower sealing roller 123. It is supported on a stationary shaft 139 (Fig. 2), the ends of which are bolted to side rails or levers 140 and 141 pivoted at one end on bar 124 and connected at the other end by an integral plate 142 on which is a centrally positioned lug 143 through which passes a rod 144. The upper end of rod 144 (Fig. 5) is provided with an enlargement 145 which is free to swing about a stationary horizontal tie rod 146. The lower end of rod 144 is provided with nuts 147 and an encircling coiled spring 148 whereby lug 143, and consequently, roller 137, are urged upwardly. This yielding support for roller 147 is of importance in insuring a clear imprint regardless of reasonable variations in the thickness of the filled envelope.

Referring to Fig. 5 cover plate 14 has a hinged extension 149 pivoted to it on each side by a bolt 150 so that the extension can be swung through 180° to bring the printing roller bottom side up as shown in Fig. 15. This is of convenience when the roller is to be cleaned or the dies or type are to be changed.

As will appear from Figs. 9-11, inclusive, the hinged extension 149 carries depending side plates 151 and 152 bolted thereto. A stationary bar or shaft 153 (Fig. 10) is bolted between these plates and is provided at its respective ends with spacing sleeves 154 and 155 (Fig. 10) between which the printing drum and its driving pulley are mounted. Mounted to turn freely on bar 153 is a wooden sleeve 156, and fitted to that sleeve with a driving fit is a driving pulley 157 having a rubber facing 158. This pulley is driven by frictional engagement with the lower spring-pressed roller 137 or with an envelope passing between the two.

At the side of driving pulley 157 and en-

circling the wooden sleeve 156 and initially driven thereby by frictional engagement is a printing drum comprising a metal sleeve 159 having a wide flange 160 shod with a rubber ring 161.

A cheek plate 162 holds the rubber ring 161 in position. At the side of this cheek plate is a cam 163 for operating the counting mechanism as hereinafter described.

The printing drum also comprises a collar 164 having a beveled side as shown in Fig. 10 for engagement with the removable printing die holder 165, the details of which are hereinafter described. Cooperating therewith is a second collar 166 having a beveled engagement with the die holder, and also bearing a lug 167 which engages in a recess on the die holder to insure proper positioning of the die holder and proper timing with other parts of the device. Collar 166, die holder 165, collar 164, cam 163, and cheek plate 162 are all rigidly clamped together and against flange 160 by a nut 168 threaded to the end of sleeve 159. Collar 166 projects out beyond nut 168 and has two notches 169 and 170, the purpose of which is mentioned hereinafter.

The printing operation must be so timed that the imprint will be impressed in its proper place on the envelope. Also for certain classes of work it is desirable to seal the envelopes without printing anything on them. These needs are taken care of in the present machine by a latching device controlled in position and in operation by a hand lever accessible at the end of the machine. Similarly it is at times desirable to throw the inking mechanism out of action. These details of the complete machine will now be described, reference being had to Figs. 6-11, inclusive.

Referring to Fig. 7 which is a vertical section on the line 24-24 of Fig. 10, there is a dog 171 mounted on a hub of sleeve 159. The nose of this dog is in position for engagement with a latch 172, Fig. 7, this latch being pivoted at 173 on a metal bracket 174. Many of the parts now to be described are shown in Fig. 7 in two positions, the full line position showing normal operation when the printing mechanism is to print on the envelope. Integral with latch 172 is an arm 175, the free end of which is in proximity to a lever arm 176' pivoted at 177 on a sheet metal bracket 178 and having an integral off-set lever arm 176. Coacting with lever arm 176 is a hand lever 179 pivoted at 180 to a pair of brackets 181 mounted on a transverse supporting plate 182 (Fig. 4). Coiled tension springs 183 secured at one end to lever 179 and at the other end to bracket 181 act on the principle of a toggle to yieldingly hold lever 179 in one or the other of the two positions shown in the drawings.

When the envelope comes through between the sealing rolls, it engages a row of yielding fingers 184 (Figs. 7 and 11) all of which are rigidly secured to a casting 185 pivoted 5 on a pair of stub shafts 186. Thus casting 185 is suspended between supporting arms 187 and 188. The former is bolted to the side plate 152 as shown in Fig. 11, and the latter is bolted to the under surface of the 10 hinged extension 149 of the cover plate 14, as shown in Fig. 11. Casting 185 carries a pair of integral lugs through which is a shaft 189. Pivoted on that shaft is a pawl 190, the working nose of which engages with 15 one arm 191 of a bell crank lever pivoted at 192. Another arm 193 of the bell crank lever has its working nose against the lowermost notched corner of latch 172. A compression spring 194 bears at one end on a 20 shoulder 195 integral with latch 172 and arm 175 and bears at its other end on a shoulder 196 integral with arms 191 and 193.

With the elements in the position shown in 25 full lines in Fig. 7 the operation is as follows:

An envelope 125 moving forward through the sealing rolls will strike fingers 184 and swing them upward to the dotted position, 30 simultaneously rocking arm 185 about pivot 186. The tail end of pawl 190 engages casting 185 and 197 and so is forced to move forward into the dotted position, thereby swinging arm 191 about its pivot 192 and 35 thus disengaging arm 193 from dog 171. Spring 194 effects unlatching as soon as the latch is released, forcing latch 172 into the dotted position. This leaves dog 171 free to turn, thus releasing the printing roll so that 40 it can be driven by the frictional engagement between sleeve 159 and the wooden sleeve 156 on which it is mounted. This brings the printing die and type into rolling engagement with the moving envelope as it 45 passes over roller 187 and in properly timed relation thereto. But after dog 171 swings through the greater part of a circle its nose strikes the lower edge of arm 175 which then is being held in the dotted line position by 50 spring 194 with its tail end seated against the under face of bracket 174, forcing that arm upward and thus forcing latch 172 back to the full line position, while the bell crank lever 193, under the action of spring 194, resumes its original position and locks the 55 latch 172. Ultimately dog 171 strikes again on latch 172 and is stopped thereby.

Effective driving connection between dog 171 and sleeve 159 is effected by means of 60 three pins 198, 199 and 200, and a leaf spring 201. These pins project from flange 160 of sleeve 159. The spring is wrapped around pin 199 and has one end hooked under pin 200, and the other end riding on

the upper edge of dog 171. Pin 198 serves 65 as a stop for the dog. As soon as the printing drum has made part of a revolution the rubber face 161 of flange 160 engages the envelope and assists in driving the printing roll. 70

With the several parts restored to their initial position, as above described, pawl 190 can clear the lower corner of arm 191, but to swing that pawl completely back to the full line position, there is provided a spring 202 75 coiled about pivot 189 as shown in Fig. 11.

The foregoing description illustrates the normal printing operation with the imprint of the type timed to fall on the stamp and adjacent parts of the envelope, the printing 80 drum making but one revolution for each envelope and in timed relation with the movement of that envelope.

When the machine is to be used for sealing envelopes without doing any printing on 85 them, hand lever 179 (Fig. 7) is thrown upward into the dotted position thus bringing its arm 203 against the beveled end of lever arm 176, forcing that end downward. The opposite lever arm 176' is thereby forced upward engaging arm 175 and acting as a stop against downward swinging movement thereof. Then when an envelope comes through, the resultant swinging of bell crank 90 lever 193 and compression of spring 194 cannot operate to swing latch 172, but leaves that latch in permanent engagement with dog 171. Under these conditions the printing drum will not rotate.

To give adequate clearance for transit of 100 the envelope on which no printing is to be done, flange 160 and its rubber face 161 are flat for a portion of their periphery as shown in Fig. 8, and so do not touch the travelling envelope and are not driven thereby, there being adequate clearance beneath the flat face as shown in Fig. 10.

The die holder is so constructed that for 105 this locked condition of the printing mechanism there is adequate clearance between it and the lower printing roll 137, as will be clear from Fig. 6.

The means for supplying ink to the printing die and type comprises an inking roller 106 204 (Fig. 6) rotatable on a pivot 205 which is supported between the lower ends of a pair of arms 206 which in turn are pivoted on a bar 207 and are connected together along one edge by an integral strap 208. Bar 207 is supported in a U-shaped bracket 110 209 bolted to plate 149. This U-shaped bracket has a downwardly extending finger 210 which carries a pair of bolts 211 over each of which fits a horizontal coiled spring 212. The other ends of those springs are seated over the ends of bolts threaded into strap 208. These bolts also secure in position on strap 208, a bent plate 213 which 115

serves as a cam. The means for camming that plate downward about the pivot shaft 207 and thereby swinging the inking roll 204 into the dotted position and out of contact with the printing die, comprises a roller 214 mounted on the bent end of a push bar 215. That roller is provided with shrouds 216 which run along on the under surface of bracket 209. Rod 215 is slotted for guidance over a screw 217 carried by bracket 178. The other end of push bar 215 is pivoted to a bell crank lever 218, like lever 179 of Fig. 7. With the parts in the position shown in Fig. 6 the inking roller is against the printing surface and by raising lever 218 to the dotted position the inking roller can be thrown out of action.

Strap 208 is so positioned that it almost contacts with the under surface of bracket 209 when the inking roller is working thus allowing proper contact with the type and yet when the type faces have passed from contact preventing the inking roller from swinging far enough forward to ink or smear the irregular surfaces of the die holder.

Counting mechanism.

As a means for keeping count of the number of envelopes or other articles on which a printed impression has been made, use is made of the cam 163 which, as heretofore described in connection with Fig. 10, is rigidly mounted on sleeve 159 and rotates therewith.

Cam 163, (Fig. 10), in addition to being firmly clamped against cheek plate 162 by nut 168 on sleeve 159, has a horizontal pin 198 (Figs. 7 and 8), heretofore mentioned, which protrudes through cheek plate 162 and flange 160, thereby anchoring cam 163 to the adjacent parts and compelling it to rotate therewith.

As shown in Fig. 8, cam 163 is engaged by a roller 219 mounted on the end of a swinging arm 220 which is rigidly attached to a horizontal rock shaft 221 pivoted in bracket 178. Also secured to rock shaft 221 is a second arm 222 carrying at its outer end a pin 223 for engagement in the bifurcated end of a finger 224 rigidly mounted on a rock shaft 225. Shaft 225 is the rock shaft of a counter as hereinafter described.

Inasmuch as cam 163 (Fig. 8) rotates clockwise, its engaging roller 219 will be cammed out and back once for each revolution of the printing drum.

When the printing drum is inactive, the counter is likewise inactive, and to render the counter inactive while leaving the printing drum active, there is provided a disengaging mechanism now to be described by reference to Figs. 4, 8 and 9.

A hand lever 226 identical in detail with hand lever 179 and mounted alongside the latter on plate 182 at the end of the machine is arranged for rocking movement on a

pivot 227. Its bent end 228 (Fig. 8) is positioned to strike against an arm 229 mounted to swing about a rigid vertical bolt 230. Integral with arm 229 and offset vertically with respect thereto is a second and smaller arm 231 (Fig. 4) which can swing in a horizontal plane and which engages one end of rock shaft 221. Consequently, upward movement of hand lever 226 into the dotted position of Fig. 8 will push rock shaft 221 endwise far enough to disengage roller 219 from cam 163 by axial movement of the roller. A coiled compression spring 232 serves to return cam 163 into alignment with the face of cam 163 when the control lever 226 is again depressed. This same spring, acting in torsion as shown in Fig. 4, serves to hold roller 219 against the working face of cam 163 during normal operation of the counting mechanism, and likewise controls the swing of the associated parts. Connection is established between rock shaft 221 and a counter 223 of usual type (Fig. 4) by means of the arm 222 and its associated swinging arm 224. Counter 223 is detachably bolted to a bracket 234 which in turn is bolted to the side plate 151, thereby making the counter easily accessible for removal when occasion requires. The upper or reading face of the counter protrudes through plate 149 as shown in Fig. 8.

The hinged extension of the cover plate (Figs. 1, 3, 4, 5 and 6).

As heretofore explained, cover plate 14 has an extension 149 (Fig. 1) hinged on bolts 150 so that plate 149 and the mechanism supported by it and its associated side plates 151 and 152 can be swung over bottom side up to the position shown in Fig. 15, thereby giving access to the relatively intricate parts of the printing drum and its die holder.

Referring to Figs. 3, 5 and 15, and for convenience viewing Fig. 15 upside down, there will be found a main shaft 235 which is free to turn inside plates 151 and 152 and at each end is held against longitudinal movement by a washer 236 and a bolt 237 tapped into the shaft as shown in Fig. 3. Immediately adjacent the washer 236, the shaft 235 has a square cross section to accommodate a handle 238 on the side face of which is an eccentric circular shoulder 239 for engagement with a circular recess in a swinging latch 240. Thus latch 240 is free to swing on shoulder 239, and the latter acts as a cam to raise or lower 240 as viewed in Fig. 3. A hook 241 (Fig. 15) on the lower end of latch 240 engages a projection 242 (Fig. 1) on a plate 243 bolted to apron 9. A transverse pin 244 (Fig. 15) carried by latch 240 is movable with the latch back and forth across a slot 245 in side plate 151, but limits swinging movement of the latch.

Handle 238 has an extension 246 (Figs. 5 and 15) traversed by a horizontal pin 247 which is positioned to strike against the adjacent edge of latch 240. At the other end 5 of shaft 235 is a similar handle 248 and associated adjuncts as just described.

When the hinged extension 149 is swung from the inverted position shown in Fig. 15 to the normal working position shown 10 in Fig. 5, the operator takes hold of handles 238 and 248, or either of them, and after pushing the pair of latches 240 into position beneath the projections 242 turns handles 238 and 248 and their associated shaft 15 235 to cam latches 240 upward into tighter engagement with projections 242, thus locking the hinged element tightly in place and preventing it from rattling or from working loose when the printing mechanism is 20 running at high speed. Side play of the hinged extension 149 is prevented by a pair of lugs 249 at the corners most remote from pivot 150 where they overlap the side plates 25 17 and 9, as indicated in Fig. 5.

When the hinged member is to be released and again lifted, the operator takes hold of handles 238 and 248, or either of them, and cams the latches 240 downward to 30 release their grip on projections 242, and this movement of the handles is continued until pin 247 strikes against the adjacent edge of latch 240 and forcibly backs hooks 241 away from projection 242.

35 *The die holder and dies (Figs. 12 to 34).*

The die holder 165 (Fig. 22) has a circular bore so that it will slip over sleeve 159 (Fig. 21), that circular bore flaring outwardly at each end to accommodate the conical collars 164 and 166 (Fig. 18) as heretofore explained. The periphery of the die holder is substantially square as shown in 40 Fig. 22 but with one corner cut away to receive an angle bar 250 held in place by bolts 251 tapped into the die holder. On one face, the die holder is provided with a slot 252 having undercut or dovetail edges. The die 253 for use in this slot 252 is shown 45 in Fig. 26 and comprises a segment of a cylinder into which removable type can be inserted as hereinafter explained. On the bottom of this segmental die is a tongue 254 dovetailed to fit in slot 252. To guard 50 against inadvertent substitution of another die in place of this one, there is provided on tongue 254 a lug 255 so positioned that it can slide as a key along a slot 256 (Fig. 24). This arrangement also insures against 55 inserting the die in the guideway wrong end to. To hold the die in proper working position in the guideway, there is provided a spring-pressed cylindrical plunger 257 travelling in a cylindrical hole in die 165. There is a thumb piece 258 on this plunger

65 by which it can be retracted when the die is to be inserted. With the die in its final position, thumb piece 258 is released and spring 259 advances the plunger, bringing a lug 260 at the upper end thereof into locking engagement with a slot 261 (Fig. 26) in 70 the lower face of the die. This die can bear the name of the post office in raised letters thereon, and within the circular printing area thus provided for, may be set up with movable type, a date, hour and year 75 in the manner now to be described.

Within the die 253 is a rectangular recess (Fig. 32) into which is fitted a type 262 having a width equal to that of the recess. Other type bars 263 (Fig. 34) of half that 80 width can be inserted in pairs to carry the month, the day of the month, the hour, and whether morning or afternoon. All of these type bars are provided mid-way their length with a cylindrical cut 264 (Fig. 34) so that 85 there is formed a cylindrical passage through the group of type. Holes are provided in the die in alignment therewith. A spring key 265 is inserted through these cylindrical holes to lock the type in the die. This 90 spring key 265 is of unusual shape and functions in an unusual way. It is made from a flat strip of resilient metal and comprises a pair of arms 265^a connected together by an 95 integral leaf-spring which also serves as a handle, as shown in Fig. 35. Each arm is bent backward at 265^b to form a finger 265^c which engages the type to be held by contacting therewith along the upper and lower corners of the finger, as shown in Fig. 33. 100 When this spring is compressed from its expanded condition, shown in Fig. 35, and is inserted into the cylindrical hole through the die and type the two fingers 265^c assume a relation parallel to one another and are 105 urged outward against the dies partly through resiliency at the bend 265^b and partly because of resiliency at the handle portion of the key. The frictional engagement is so good that the key does not work 110 loose and yet it can be easily and quickly removed by an unskilled operator without the aid of any special tools.

Referring again to Fig. 22, there will be 115 found a second slot 267 similar in all essential respects to slot 252 into which can be inserted the die 268 of Figs. 28 to 30. This die 268 has a dove-tailed tongue 269, the same as the other die and has a lug 270 for cooperation with a slot 271 (Fig. 23) but 120 so positioned that the die cannot inadvertently be pushed into slot 252. With this die also, there is a slot 272 into which is received the lug 273 of spring-pressed plunger 274.

125 In order that die 268 may bear the permit number of the user of the machine, it is recessed along one edge to receive an auxiliary

die 275 which can be slipped into place while the die is being pushed into its slot 267. The dove-tail tongue 276 and the beveled vertical sides of this auxiliary die lock it in working position.

It is the function of die 268 to cancel the stamp on the envelope, as shown in Fig. 36, and to print adjacent to the canceled stamp the mailer's post mark permit number. Adjacent thereto but printed by the other die of the printing drum is the name of the post office, the date, the hour and the year of cancellation.

As a convenient means for holding the die against rotation while changes in the type are being made there is provided a latch 277 (Figs. 12 and 15) pivoted on a stub shaft 278 and provided with a weight 279 at its outer end.

When the printing mechanism is in working position this latch 277 is in the position shown in Fig. 12, with its upper end resting against the inwardly bent end 152' of side plate 152, being held in that position by weight 279, and with its latching nose 280 out of contact with anything. But when the cover plate extension 149 is swung upward about bolts 150 into the inverted position shown in Fig. 15, weight 279 will drop down by gravity and bring the latching nose 280 into engagement with the cylindrical collar 166 (Fig. 10), in position to drop into notch 169, or into notch 170 (Fig. 15). When in notch 169, the die of Figs. 25-27 lies uppermost, and is easily accessible to permit sliding withdrawal of the die. Similarly, spring key 265 can be reached conveniently for withdrawal to release the type, which then can be picked out one by one with tweezers. When the other die is to be removed, the operator puts his finger under the laterally bent tail 281 of latch 277 and lifts weight 279 to swing latching nose 280 out of engagement with slot 169. The die can then be turned 90° and the latching nose will drop into slot 170 thus holding the die of Figs. 28-30 uppermost while its spring-pressed plunger is being retracted and the die slipped out of its slot.

The drive (Figs. 1, 2, and 3).

The machine as a whole is driven by an electric motor 282 (Fig. 1) with its base 283 bolted to a transverse cross bar 284 bolted to base 1, as shown. The drive is through a round belt 285 to speed-reducing pulleys 286 and 287. The latter is connected by a belt 289 to a pulley 288 (Fig. 1).

Pulley 288 drives the moistening mechanism through suitable means, and also drives the transfer means and, in turn, the sealing rolls 122 and 123 through suitable belts and pulleys. The shaft 139, which is the shaft of the lower printing roll 137, is driven through

a belt 310 and a pulley 311 from the sealing rolls, as shown in Figs. 1 and 2. Pulley 311 is slightly smaller than pulley 309 so that the printing rolls tend slightly to pull the envelopes from the sealing rolls, the ultimate tension on the envelope being safe-guarded by a ratchet connection between sleeve 306 and the lower sealing roll 123.

To operate the machine, the addressed and filled envelopes are placed horizontally in a stack on the receiving platform, with their gummed flaps hanging down in shingled relation to one another and their stamped ends toward the feeding drum. The lowermost envelope of the stack is caught between the feed rolls and pulled out from beneath the stack and advanced through the moistening device where the gummed flap thereof is moistened. After this flap is moistened, each envelope passes on through the transfer and sealing mechanism where it is sealed. The sealed envelope then passes to the printing rolls where the postage stamp is canceled and the name of the post office and the date and hour and the user's permit number are printed adjacent to the canceled stamp. The result is the same whether the postage stamp is a part of the envelope or is an adhesive stamp, for the machine is equally effective with either type of envelope.

The printing rolls can be thrown out of action at the will of the operator, the counting mechanism can be thrown out of action without interruption to the printing, and the inking roll can be thrown out of action at any time. There is no occasion for Government supervision of the counting mechanism, for each envelope bears full postage of the proper denomination, whether that postage be in the form of an imprint in the envelope or in the form of an ordinary postage stamp stuck on with adhesive. Data furnished by the counting mechanism is of interest, not to the Government, but to the user of the machine.

The user of a permit number in the printed inscription is a safe-guard against abuse of the privilege of depositing at the post office, in bulk, stamped envelopes on which the stamps have been canceled by some one other than a Government employee.

As will be clear from the above description, the machine is capable of a wide variety of uses in the handling of filled envelopes. It can, of course, be operated as a simple sealing machine, or even as a mere counter of cards and like flat objects, the latter result being effected by removing the die and throwing the inking roll out of action, thus permitting the cards to trip the printing drum, and thereby actuate the counter, but without at the same time receiving any imprint from the printing dies.

A great variety of changes may be made in details of the structure and in the mode

of operation of the several parts without departing from the spirit of the invention as defined by the appended claims.

I claim:

5. 1. In a machine of the character described, the combination of a stationary shaft, a sleeve on said shaft, a pulley fixed to said sleeve, a printing drum journalled on said sleeve and having a frictional engagement therewith, a power driven lower roll having a driving connection with said pulley, means for holding said printing drum stationary with respect to said sleeve, means for at times releasing said holding means, and 10 15 20 25 30 35 40 45 50 55 60 65 70 75 80 85 90 95 100 a rubber faced flange on said printing drum for at times establishing a driving connection between said drum and said lower roll.
  2. In a machine of the character described, the combination of a stationary shaft, a sleeve on said shaft, a pulley fixed to said sleeve, a printing drum journalled on said sleeve, said drum having a frictional engagement with said sleeve and capable of turning relative thereto, a power driven lower roll having a driving connection with said pulley, means initially holding said printing drum against rotation with said sleeve, a release for said holding means, said release being positioned for actuation by an approaching envelope, and said printing drum including a rubber faced flange which is cut away along one side, whereby a driving connection is established between said printing drum and an envelope passing between said drum and said lower roll.
  3. In a machine of the character described, a power driven lower roll, a cover plate having a hinged extension extending over said roll, means suspended from said hinged extension including a printing drum and means for establishing a driving connection between said printing drum and said lower roll when said extension is in the normal position, said drum and said driving means being adapted to be inverted when said extension is swung over into contact with said cover plate, and a latch for engaging said printing drum while in this inverted position to hold it against rotation while adjustments are being made.
  4. In a machine of the character described,
- a power driven lower roll, a cover plate having a hinged extension extending over said roll, a printing drum carried by said hinged extension, and means carried by said extension for at times establishing a driving connection between said lower roll and said printing drum when said extension is in the normal position, said printing drum and said connecting means being readily accessible when said extension is folded over against said cover plate.
5. In a machine of the character described, the combination of a cover plate having a hinged extension, a printing drum and means for controlling the operation of said drum suspended from said hinged extension, a latch for holding said extension in working position and a manually operative cam for tightening said latch to lessen vibration.
6. In a machine of the character described, the combination of a cover plate having a hinged extension, a printing drum suspended from said extension in position to be turned bottom side up when said extension is swung over to contact with said cover plate, and a latch for engaging said printing drum while in this inverted position to hold it against rotation while adjustments are being made, substantially as described.
7. In a machine of the character described, the combination of a cover plate having a hinged extension, a printing drum suspended from said extension in position to be turned bottom side up when said extension is swung over to contact with said cover plate, and a gravity actuated latch automatically engaging said printing drum when in the inverted position, thereby holding said drum against accidental rotation while changes are being made in said drum.
8. In a machine of the character described, the combination of a stationary shaft, an anti-friction wood sleeve encircling said shaft, a rubber-faced pulley securely attached to said sleeve, and a printing drum mounted on said sleeve and capable of turning thereon, said printing drum including a rubber-faced flange which is cut away along one side, substantially as described.

In testimony whereof I affix my signature.

JOHN W. ESKHOLME.
